UNITED STATES PATENT OFFICE.

JOHN SHELLY, OF ST. LOUIS, MISSOURI.

RIDING-SADDLE.

SPECIFICATION forming part of Letters Patent No. 248,514, dated October 18, 1881.

Application filed June 10, 1881. (No model.)

To all whom it may concern:

Be it known that I, JOHN SHELLY, of the city of St. Louis, in the State of Missouri, have invented a certain new Improvement in Saddles, of which the following is a full, clear, and exact description, reference being had to the accompanying drawings, forming part of this specification.

My improvement consists in a riding-saddle constructed with a metal back-plate adapted to fit the back of the animal and a metal seat-plate fitting the person of the rider, the plates being rigidly connected, forming an air-space between them, as set forth hereinafter.

15 In the drawings, Figure 1 is a side view of the saddle. Fig. 2 is a front view. Fig. 3 is a back view. Fig. 4 is a top view. Fig. 5 is a section at $x x'$, Fig. 4. Fig. 6 is a section at $x' x'$, Fig. 4.

20 A is the bottom plate, having the convex cheeks $a a$, fitting the back of the animal each side of the spine, and the spinal groove a' , to relieve the spine from pressure, as required in a saddle. The plate A is shown with numerous perforations, a^2 , to allow the free ventilation of its lower surface to keep the back of the animal cool and dry. The plate A may be perforate, as shown, or may be imperforate.

25 B is the seat-plate, formed to fit the person of the rider.

The plates A and B, I have shown attached together by screws or rivets at C, which also

pass through the upper parts of the skirts D, said part being interposed between the edges of the plates.

35 E are rings for the attachment of any article to the saddle.

It will be seen by reference to Figs. 2, 3, 5, and 6 that there are spaces F for the free passage of air between the back-plate A and the 40 seat-plate B, so that both plates are kept cool by the air-current, and where the plates are perforated their outer faces are ventilated.

45 The perforations of the plate B are shown in Fig. 4.

The metal plates A or B, or both, may be covered with leather or other material, or uncovered.

I have described my improvement as applied to men's saddles; but it is very evident that 50 it is equally applicable to side-saddles.

I claim as my invention—

1. In a riding-saddle, the combination of metal back-plate A and metal seat-plate B, constructed substantially as set forth.

2. A saddle composed of metal back-plate A, fitting the back of the animal, and metal seat-plate B, fitting the person of the rider, the plates being rigidly connected, forming an air-space between them, as set forth.

55 JOHN SHELLY.
